UNITED STATES PATENT OFFICE

FRITZ F. PETERSEN, OF SAN FRANCISCO, CALIFORNIA

AEROPLANE ROTOR

Application filed March 1, 1932. Serial No. 596,001.

This invention relates to a construction of an improved rotor employed to impart non-stalling support and lift to an aeroplane. In certain respects this invention 5 comprises certain specific improvements over that invention disclosed in my copending application Serial No. 589,660, filed January 29, 1932, and in other respects this invention is generic thereto.

10 It is an object of the present invention to provide a new and improved rotor for an aeroplane.

Another object of the present invention 15 is to devise a rotor for providing lift and support for an aeroplane, which can be controlled and manipulated to vary selectively operative portions of the rotor.

A further object of the present invention 20 is to provide an aeroplane rotor which can be manipulated during flight to provide non-stalling lift and support to an aeroplane during maneuvering of the aeroplane.

A further object of the present invention 25 is to provide a rotor mechanism for an aeroplane, a portion of which can be varied selectively to change the degree of effective use of the rotor in providing lift and non-stalling support during maneuvering of the aeroplane upon which it is employed.

30 A still further object of the present invention is to provide means for selectively varying the ailerons provided on a rotating blade during rotation.

35 I accomplish these and other objects by means of the improved device disclosed in the drawings forming a part of the present application wherein like characters of reference are used to designate similar parts thruout the specification and drawings, and 40 in which:—

Fig. 1 is a plan view of a preferred form of aeroplane rotor of my invention.

Fig. 2 is a section along the line 2—2 45 of Fig. 1 showing the contour of the blade and aileron and means for varying the aileron relative to the blade.

Fig. 3 is a view, the left hand portion of 50 which is in section and the right hand portion of which is an elevation of the aileron control means.

Fig. 4 is a view along the line 4—4 in Fig. 3 showing the construction of the means for varying selectively the ailerons.

Fig. 5 is a side view of the control stick 55 for the ailerons.

Fig. 6 is a view along the line 6—6 of Fig. 5, showing how the cables are connected to the control stick.

In accordance with this invention, I provide a plurality of blades 1 which extend 60 radially from the common center of hub 2 to which they are fixed. Intermediate the ends of the blades 1 position an annular wing 3 which is preferably discontinuous adjacent each blade. Thus, outer and inner ring 65 members 4 and 5 are extended between adjacent blades to join them together and to provide a support upon which the wing 3 can be fabricated or mounted. The full length of each blade is thus free to engage 70 the air to act thereon.

Each blade has a leading edge 6 and a trailing edge 7, the blades being suitably contoured. At each blade trailing edge 7 I 75 secure ailerons 8 and 9 on rotatable shaft 11. Ailerons 8 are preferably positioned between rim members 4 and 5 while ailerons 9 are positioned along the trailing edge of the blades between inner ring member 5 and hub 2. The outline and contour of the annular wing, the blades and the ailerons are such that a self-rotating, balanced rotor is available to supply lift and non-stalling support to an aeroplane as the rotor rotates about shaft 12 which supports hub 2. 80

Means are provided for selectively varying the ailerons and for moving them automatically during rotation of the rotor. Cables 13 extend from each aileron 9 thru slots 10 in the blades to bell cranks 14 which 90 are mounted for hinged movement in recesses 16 in the blades. Since the ailerons 8 and 9 are secured to rotatable shaft 11, movement of a cable 13 is effective to move simultaneously, and an equal amount, both 95 ailerons 8 and 9.

Each bell crank 14 includes a crank arm 17 which engages a groove 18 in a ring 19. Ring 19 is mounted for universal movement by a gimbal which includes another ring 22 100

mounted for hinge movement by pins 23 in shaft 12 and ring 22. Ring 19 carries pins 24 providing a hinge with ring 22. Pins 23 are in a plane 90° removed from a plane 5 containing pins 24 so that the ring 19 can move universally. Ring 19 carries eyes 26 from which cables 27 extend to a suitable control mechanism as stick 28 located in the aeroplane convenient to the pilot. Stick 28 10 is mounted for universal movement by ball and socket 29. Cables 27 are passed over guides 30 and are attached to cross 31 on stick 28 so that when stick 28 is moved, the ring 19 is moved likewise and the ailerons 15 are moved relative to the blades during rotation of the rotor. Pins 32 extending from ring 19 into grooves 33 in ring 22 limit movement of ring 19 relative to ring 22 while pins 34 extending into grooves 35 in shaft 20 12 limit movement between ring 22 and shaft 12. The total free universal movement of the ring 19 is thus limited.

While the rotor is capable of self rotation 25 when moved relative to the air, I preferably include means for rotating the rotor positively. Ring gear 36 is secured to blades 1 and hub 2 by bolts 37. A pinion gear 38 drives the ring gear from a shaft 39 upon 30 which the pinion gear is mounted in a supporting casing 41. Shaft 39 carries universal 42 connected to shaft 43 which extends to a suitable source of power and is driven therefrom selectively when desired, as I have disclosed in my aforementioned 35 pending application.

Shaft 12 is hinged about pin 44 which is carried by a suitable supporting structure 46 on the aeroplane. Arms 47 extend from casing 41 and carry cables 49 which extend 40 to suitable control mechanism so that shaft 2, and the rotor carried thereby, can be adjusted angularly fore and aft of the aeroplane to enable the center of lift of the rotor to be varied and to enable the angle of the 45 rotor to the direction of flight to be varied, as I have particularly disclosed in my aforementioned copending application.

The ailerons are selectively operated when 50 the aeroplane is to be banked by the stick 28 to make a turn or when a climb is to be undertaken or a descent made. The rotor provides non-stalling support so flexible in character and of such an amount that the stub wing, usual to aeroplanes of this type, 55 can be dispensed with and the controls of the aeroplane simplified. The rotor is capable of hinge movement about pin 44 so that the rotor can be moved relative to the direction of flight of the aeroplane to cause autogiration, if desired, quickly and without positive driving when a take-off is undertaken.

The ailerons are the only flexible elements 60 in the structure, thus simplifying the construction. The centrifugal forces arising

upon rotation are counterbalanced against each other, and are taken up thru a relatively solid structure, thereby making the operation of the rotor smooth and with greater efficiency.

Having thus described my invention what I claim as new and desire to secure by Letters Patent is—

1. An aeroplane rotor comprising a plurality of blades extending from a common center, and an annular wing joining said plurality of blades, said wing being discontinuous adjacent each of said blades. 70

2. An aeroplane rotor comprising a plurality of blades extending from a common center, an annular wing joining said plurality of blades, said wing being discontinuous adjacent each of said blades, and a movable aileron on each of said blades. 80

3. An aeroplane rotor comprising a plurality of blades extending from a common center, an annular wing joining each of said blades and an aileron trailing each of said blades. 85

4. An aeroplane rotor comprising a plurality of blades extending from a common center, an annular wing joining each of said blades, said wing being discontinuous adjacent each of said blades, and an aileron trailing each of said blades adjacent said discontinuous wing. 90

5. An aeroplane rotor comprising a plurality of blades extending from a common center, an annular wing joining each of said blades, said wing being discontinuous adjacent each of said blades, an aileron trailing each of said blades adjacent said discontinuous wing, and another aileron trailing each of said blades between said wing and said center. 95

6. An aeroplane rotor comprising a plurality of blades extending from a common center, an annular wing joining each of said blades, said wing being discontinuous adjacent each of said blades, an aileron trailing each of said blades adjacent said discontinuous wing, and means to vary selectively the position of each of said ailerons to each of said blades. 100

7. An aeroplane rotor comprising a plurality of blades extending from a common center, an annular wing joining each of said blades, said wing being discontinuous adjacent each of said blades, an aileron trailing each of said blades adjacent said discontinuous wing, another aileron trailing each of said blades between said wing and said center, and means to vary selectively the position of each of said ailerons to each of said blades. 110

8. An aeroplane rotor comprising a plurality of blades extending from a common center, an annular wing, joining said plurality of blades, said wing being discontinuous adjacent each of said blades, a movable aileron on each of said blades, and means to 120

125

130

vary selectively the position of each of said ailerons to each of said blades.

9. An aeroplane rotor comprising a plurality of blades extending from a common center, an annular wing joining said plurality of blades, said wing being discontinuous adjacent each of said blades, a movable aileron on each of said blades, and means to vary selectively the position of each of said ailerons to each of said blades in a predetermined manner upon rotation of said rotor.

10. An aeroplane rotor comprising a plurality of radial blades, an annular wing joining said blades and discontinuous adjacent each of said blades, a first aileron trailing each of said blades adjacent said discontinuous wing, a second aileron trailing each of said blades inside of said wing, and means to vary selectively said ailerons.

20 11. An aeroplane rotor comprising a plurality of radial blades, an annular wing joining said blades and discontinuous adjacent each of said blades, a first aileron trailing each of said blades adjacent said discontinuous wing, a second aileron trailing each of said blades inside of said wing, and means to vary selectively said ailerons in a predetermined manner during rotation of said rotor.

20 12. An aeroplane rotor comprising a hub, a shaft for supporting said hub for rotation, a plurality of blades extending from said hub, an aileron on each of said blades, a grooved ring mounted for universal movement on said shaft, means for moving said ring, and means connecting said ring to said ailerons, including a bell crank engaging said grooved ring, whereby said moving means control said ailerons.
